(57) **CLAIM**

The ornamental design for a stamp component for transferring microstructure, as shown and described.

DESCRIPTION

FIG. 1 is a perspective view of a stamp component for transferring microstructure, showing our new design; FIG. 2 is a front elevational view thereof, the rear elevational view being identical thereto; FIG. 3 is a left side elevational view thereof, the right side elevational view being identical thereto; FIG. 4 is a top plan view thereof; FIG. 5 is a bottom plan view thereof; FIG. 6 is an enlarged portion view labeled, "6," in FIG. 1; FIG. 7 is an enlarged portion view labeled, "7," in FIG. 6; FIG. 8 is an enlarged portion view labeled, "8," in FIG. 2; and, FIG. 9 is an enlarged portion view labeled, "9," in FIG. 8.
(Continued)

The dot-dashed lines depict the boundaries of the enlarged portion views of FIGS. 6-9 in FIGS. 1, 2, and 6-9 and form no part of the claimed design.
